US0D1005471S

(12) **United States Design Patent** (10) **Patent No.:** **US D1,005,471 S**
(45) **Date of Patent:** **** Nov. 21, 2023**

(54) **PORTABLE ELECTRIC FAN**

(71) Applicant: **Quanguo Zou**, Hubei (CN)

(72) Inventor: **Quanguo Zou**, Hubei (CN)

(**) Term: **15 Years**

(21) Appl. No.: **29/894,521**

(22) Filed: **Jun. 9, 2023**

(51) **LOC (14) Cl.** 23-04

(52) **U.S. Cl.**

USPC **D23/370**

(58) **Field of Classification Search**

USPC D23/332, 335-336, 370, 381

CPC F24F 7/00; F24F 7/007

(57) **CLAIM**

The ornamental design for a portable electric fan, as shown and described.

DESCRIPTION

FIG. 1 is a front, right and top perspective view of a portable electric fan, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded view of the portable electric fan of FIG. 1;

FIG. 10 is a front, right and top perspective view of the portable electric fan of FIG. 1 in a first configuration of use; and,

FIG. 11 is a front, right and top perspective view of the portable electric fan of FIG. 1 in a second configuration of use with environmental subject matter.

The broken lines depict portions of the portable electric fan that form no part of the claimed design. The additional broken lines in FIG. 11 depict environmental subject matter that forms no part of the claimed design.

1 Claim, 11 Drawing Sheets
